UNITED STATES PATENT OFFICE.

JAMES H. HILL, OF ROCHESTER, NEW YORK, ASSIGNOR TO EMBURY MANUFACTURING CO., OF WARSAW, NEW YORK.

DESIGN FOR A TUBULAR LANTERN.

44,340.

Specification for Design.

Patented July 15, 1913.

Application filed April 24, 1913. Serial No. 763,451. Term of patent 7 years.

To all whom it may concern:

Be it known that I, JAMES H. HILL, a citizen of the United States, residing at Rochester, in the county of Monroe and State of New York, have invented a new, original, and ornamental Design for Tubular Lanterns, of which the following is a specification, reference being had to the accompanying drawing, forming part thereof.

Figure 1 is an elevation, and Fig. 2 is a

plan view of a lantern showing my new design.

I claim:

The ornamental design for a tubular lantern as shown.

JAMES H. HILL.

Witnesses:

B. B. CONABLE,
W. C. EMBURY.
